UNITED STATES PATENT OFFICE.

WILLIAM HOSKINS, OF CHICAGO, ILLINOIS.

PROCESS OF SEPARATING SUSPENDED PULP.

1,226,333.

Specification of Letters Patent.

Patented May 15, 1917.

Application filed October 15, 1915. Serial No. 56,161.

To all whom it may concern:

Be it known that I, WILLIAM HOSKINS, a citizen of the United States, residing at Chicago, in the county of Cook and State of Illinois, have invented a new and useful Improvement in Processes of Separating Suspended Pulp, of which the following is a specification.

My invention relates to the art of recovering suspended pulp from liquids carrying the same. More particularly, the invention is applicable to paper pulp mills in which the waste-water contains sulfite liquor and a certain proportion of finely-divided pulp held in suspension. The specific gravity of these wetted particles of pulp is so close to that of the water that it is exceedingly difficult to effect their precipitation in any practical form of settling tank. Instead of attempting to precipitate this pulp, I therefore propose to separate the same from the waste-water by causing the pulp to rise to the surface and remain there as a scum or floating stratum which may conveniently be skimmed off.

An apparatus suitable for effecting this result is illustrated by the accompanying drawing in which there is shown a body of the waste-liquor indicated by the numeral 1 and carrying in suspension particles of finely-divided pulp, 2. The liquor may be held in any desired form of tank but it is not necessary that any special structure be provided, the usual open channels which 30 drain off the waste-liquor being sufficient if they are large enough in cross-section to limit the velocity to a reasonable figure. In the drawing, the numeral 3 designates the bottom of such an open channel, the direction of flow of the liquid in the channel being shown by the arrow therein. At the outer end of the channel there is provided a dam 4 of any suitable form extending above the surface of the liquid and having an aperture 5 near the bottom through which the liquid flows.

The channel bottom 3 is covered with a thin layer of natural limestone 6 which may extend up the channel away from the dam 50 for any desired distance, depending upon the width of the channel, and the velocity and depth of the liquid body therein, as will later appear.

The liquid body being thus dammed at its 55 upper surface and contacting with a bottom

of limestone, the following action will take place: the sulfites contained in the liquor will react upon the limestone to liberate carbon dioxid gas, the bubbles of which as formed will rise through the liquid body 60 and in their upward passage will attach themselves to the suspended pulp particles, which will thereby be carried upwardly to the surface, forming a scum or surface stratum very rich in pulp. This scum will 65 float downward until it is arrested by the dam, and may be skimmed off at that point or pumped or run off or removed by any desired means.

From the foregoing it is apparent that 70 the purposes of the present invention may best be fulfilled where the body of liquid is relatively quiescent, that is, where the velocity of the water is low enough to permit each portion of it to remain in contact with 75 the limestone long enough to effect the desired generation of gas and flotation of the suspended matter by this gas as it rises through the liquid body.

While I have illustrated and described in 80 some detail one application of my new process and the means for applying the process, these details are illustrative only, and for the purpose of making my invention more clear and I do not regard the invention as 85 limited to such details of either construction or use, except in so far as I have included the same within the terms of the following claims.

What I regard as new and desire to se- 90 cure by Letters Patent is:—

1. The method of separating from a liquid-body consisting of or containing in solution a chemically-active constituent, paper pulp suspended therein, which consists in 95 bringing the liquid into contact with an immersed solid of a character which is acted upon by the said constituent to liberate gases, whereby the liberated gases rise from the immersed solid and in passing upwardly 100 carry with them to the surface the said suspended pulp to form of the latter a scum or surface stratum, and removing the said scum or surface stratum.

2. The method of separating from an acid 105 liquor paper pulp suspended therein, which consists in bringing the liquor into contact with an immersed carbonate which is attacked by the said acid to liberate carbon dioxid, whereby the carbon dioxid will rise 110

through the liquor and carry to the surface thereof the suspended pulp, forming of the latter a surface stratum or scum, and removing the said scum.

5 3. The method of separating suspended pulp from sulfite waste-waters which consists in passing the said waters over im-

mersed limestone, and removing the resultant pulp-carrying surface-stratum.

WILLIAM HOSKINS.
